UNITED STATES PATENT OFFICE.

JAMES E. COLLINS, OF DANVERS, MASSACHUSETTS, ASSIGNOR TO UNITED SHOE MACHINERY COMPANY, OF PATERSON, NEW JERSEY, A CORPORATION OF NEW JERSEY.

MACHINE FOR THICKENING THE EDGES OF SOLES.

1,093,035.

Specification of Letters Patent.

Patented Apr. 14, 1914.

Application filed May 25, 1906. Serial No. 318,733.

To all whom it may concern:

Be it known that I, JAMES E. COLLINS, a citizen of the United States, residing at Danvers, in the county of Essex and Commonwealth of Massachusetts, have invented 5 certain Improvements in Machines for Thickening the Edges of Soles, of which the following description, in connection with the accompanying drawings, is a specification, like reference characters on the drawings indicating like parts in the several figures.

This invention relates to machines for thickening and preferably somewhat condensing the edges of stock, such as soles of boots and shoes. By the term "edge" is meant that part which is adjacent to the outer limit of the sole.

Heretofore in thickening or condensing 20 the edges of soles, so far as I am aware, no provision has been made for maintaining their size or width. The soles are died out or cut to a particular size, and it is desirable that this size be not changed during 25 the thickening and condensing operation. This invention therefore preferably provides for maintaining the size or width of the sole.

One of the objects of this invention is to 30 thicken the edges of soles so that if it be desired to remove a thin shaving from the upper side around the edge, subsequently to securing the sole and upper together, but prior to edge trimming, as in the operation 35 of fleshing, the original thickness of the edge of the sole will not be reduced by that operation.

Another object is to condense somewhat 40 the material constituting the edge, whereby a cleaner cut is made by the edge-cutting tool during the edge-trimming operation.

A further object of this invention is to 45 form a groove or depression in the upper side of the sole extending around inside of the edge. This groove is deepest where the lower edge of the upper fits upon the sole, and inclines upwardly, whereby an abrupt bend of the upper is prevented as it turns away from the sole in some kinds of shoes. 50 The edge of the upper fits down into this groove, thus preventing a projection of the upper above the surface of the sole at the meeting point.

A further object is to condense the ma-

terial beneath the groove or depression. This 55 portion of the sole, being thinner than the remaining portion, would wear through more quickly were it not rendered more wear-resisting by condensing it.

The objects of this invention are best secured by using a machine which has a support for the sole and a conical roll which acts upon the side of the sole opposite that engaged by the support in such a way as to crowd material outwardly toward the edge 65 of the sole, at the same time condensing it and forming a groove or depression in the sole inside of the edge. The surface of the conical roll is preferably provided with a series of grooves extending diagonally of 70 the surface in such a manner that they tend to work the material toward the outside of the edge of the sole. In order to maintain the size of the sole, an edge guide is provided against which the material that is 75 moved outwardly walls up instead of spreading outwardly beyond the original edge of the sole.

In the drawings,—Figure 1 is a perspective view of the machine; Fig. 2 is a side 80 elevation, partly in section, of the parts which operate directly upon the sole; Fig. 3 is a detail view showing a portion of the edge of the sole as it appears after passing through the machine, and Fig. 4 is a vertical section through a shoe showing the application of the sole thereto.

A base 1 which is to be secured to a bench or other support, carries a rear standard 2 and a front standard 3. A gear 4 is 90 rotatably mounted on the standard 2, and this gear is turned by any convenient source of power, as here shown by a crank 5. A shaft 6 is rotatably mounted in bearings on the upper ends of the standards. This 95 shaft carries a gear 7 on its rear end in mesh with the gear 4, a gear 8 intermediate its ends, and a support for the stock in the form of a bed roll 9 on its front end. The upper end of the front standard 3 has an 100 enlargement 10 which carries an edge guide 11 and a stop 12, and which has a recess 13. The edge guide is preferably in the form of a rotatable roll. An auxiliary frame 14 is pivoted at 15 to two ears 16 and 17 on 105 the upper end of the standard 2. The front portion 18 of this auxiliary frame forms a bearing for a shaft 19 which has a bear-

ing also in the rear part of the frame. A bifurcated extension 20 is secured to the upper end of the standard 3, and the bearing 18 which is preferably squared passes between the arms of the bifurcation. The shaft 19 carries a gear 21 on the rear end in mesh with the gear 8, and a presser roll 22 on the front end. The presser roll has a conical surface 25 which preferably merges into a cylindrical surface 26, and a reduced portion 23 for the accommodation of the edge guide 11. The conical surface may be provided with grooves which are preferably inclined to the elements of the cone so as to extend diagonally of the conical surface. The presser roll is removably held on the shaft 19 as for example by the nut 24 which permits removal for repair or for the substitution of a new presser roll. The bearing 18 is held down by a stiff spring 27, the tension of which may be regulated by a set screw 28. A rock shaft 29 passes through the extension 20 and the recess 13, and it carries the tappet cam 30 which lifts the bearing 18 and the presser roll 22 when the shaft is rocked. This lifting of the presser roll permits insertion and removal of the stock. The shaft is rocked by means under the control of the operator as by an arm 31 rigidly secured to the shaft and pivotally secured to a rod 32 having a treadle (not shown) at its lower end.

The operation of the machine is as follows: Upon turning the gear 4, power is transmitted through the gear 7 to the shaft 6 to turn the bed roll 9. The gear 8 by meshing with the gear 21 in turn transmits power to the shaft 19 so that the presser roll 22 is turned in the opposite direction from the bed roll. Upon rocking the shaft 29 the auxiliary frame 14 is turned upon the pivot 15 and the presser roll 22 raised to permit insertion of the stock *a* between the two rolls. The rock shaft is then released and the presser roll is forced down upon the stock by the spring 27 acting upon the bearing 18. The sole is fed through between the rolls by turning them in the direction indicated by the arrows in Fig. 1. The sole is kept in contact with the edge guide 11, and the material which the presser roll crowds toward the outer limit *c* of the edge is banked up against this guide and the size of the sole thus maintained. The conical shape of the roll tends to produce a transfer of material in the tempered sole toward its edge, and the diagonally arranged grooves increase this tendency, their effect resembling that of a screw conveyer. Since the guiding face of the roll is contiguous to the ends of the bed and presser rolls, these three rolls together form a pocket into which material is forced constantly, and by which it is shaped. The

material in this pocket is put under pressure by the action of the presser roll and the result is the condensing previously mentioned. The presser roll therefore performs three important functions, viz.: thickening, condensing and grooving the sole. The conical portion 25 of the presser roll forms the depression *b* while the cylindrical portion 26 forms the surface *d* parallel to but higher than the main upper surface of the sole. Fig. 4 shows the sole applied to a McKay shoe. The lower edge of the upper fits into the inclined depression *b* and the abruptness of the bend is thus diminished. It will also be seen that the depression provides a clearance for the upper.

While in the above description a complete machine has been described in detail in order to fully set forth the preferred manner of applying the invention, it will be understood that various changes may be made in arrangement and details without departing from the spirit of the invention.

Having described my invention, I claim as new and desire to secure by Letters Patent of the United States:—

1. In a machine of the class described, the combination with means for thickening the extreme edge portion of a sole, of means for maintaining the initial size of the sole. 95
2. In a machine of the class described, the combination with means for thickening and condensing the edge of a sole, of means for maintaining the initial size of the sole. 100
3. In a machine of the class described, the combination with means for thickening and grooving the extreme marginal portions of a sole, of means for maintaining the initial size of the sole. 105
4. In a machine of the class described, the combination with means for condensing the extreme marginal portions of a sole and for grooving the sole, of means for maintaining the initial size of the sole. 110
5. In a machine of the class described, the combination with means for supporting a sole, of means for thickening, condensing, and grooving the marginal portions of the sole. 115
6. In a machine of the class described, the combination with yieldingly actuated means for crowding material toward the edge of a sole and condensing the marginal portion of the sole, of means for maintaining the initial size of the sole. 120
7. In a machine of the class described, the combination with means for crowding material toward the edge of a sole and condensing the same, of means for maintaining the initial size of the sole. 125
8. In a machine of the class described, the combination with a presser roll and a bed roll constructed and arranged to engage simultaneously opposite sides of a sole at opposite points and to thicken the edge por- 130

tion of a sole passed between them, of an edge guide arranged to engage the edge of the sole while it is being acted upon by said rolls.

5 9. In a machine of the class described, the combination of a conical presser roll and a bed roll constructed and arranged to operate simultaneously on opposite sides of a sole at opposite points and to thicken the 10 edge portion of a sole passed between them, and an edge guiding roll having its guiding 15 face positioned contiguous to the peripheral edges of said presser and bed rolls.

10. In a machine of the class described, the combination with a presser roll having 15 grooves extending diagonally of its surface, and a bed roll, said rolls being constructed and arranged to thicken the edge of a sole 20 passed between the same, of an edge guide for the sole.

11. In a machine of the class described, the combination with a presser roll having a conical surface merging into a cylindrical

surface, and having a reduced portion, of a bed roll substantially cylindrical in form, 25 said rolls being constructed and arranged to thicken the edge of a sole passed between them, and an edge guide mounted contiguous to the reduced portion of said presser roll.

30 12. In a machine of the class described, the combination of a conical presser roll and a bed roll arranged to engage simultaneously opposite sides of a sole passed between them, and an edge guiding roll having its peripheral 35 face contiguous to the peripheral edges of said presser and bed rolls to form a pocket in which the part of the sole being operated upon by the bed and presser rolls is confined.

In testimony whereof I have signed my 40 name to this specification in the presence of two subscribing witnesses.

JAMES E. COLLINS.
